UNITED STATES PATENT OFFICE.

ARTHUR H. SAUNDERS, OF RICHMOND, VIRGINIA.

COLLAPSIBLE TUBE AND CUT-OFF THEREFOR.

Application filed February 24, 1922. Serial No. 538,861.

To all whom it may concern:

Be it known that I, ARTHUR H. SAUNDERS, a citizen of the United States, residing at Richmond, in the county of Henrico and State of Virginia, have invented certain new and useful Improvements in Collapsible Tubes and Cut-Offs Therefor, of which the following is a specification.

The collapsible or deformable tube, to which these improvements relate, has long since become the most popular type of container for such materials as paints, pastes, and other semi-fluctuant commodities, owing to the facility of dispensing the contents and to the large number of other advantages which do not require specific mention here. There is, however, one particular drawback possessed by these articles, and that lies in the form of the conventional closure employed for these tubes, the removable cap.

It is well recognized that the unscrewing and rescrewing of the cap of the tube every time the contents are dispensed is quite troublesome, and not infrequently the cap slips from the fingers and is either lost or dropped upon the floor, becoming contaminated and obviously, therefore, forming a rather unsanitary closure means. The user, for this reason, is tempted to and often does omit to replace the cap upon the tube, and among other results is that such omission affects the characteristics of the contents of such commodities as tooth pastes and paints.

I am well aware that many expedients have been resorted to for the purpose of overcoming these disadvantages, among which may be mentioned the enlargement of the cap so as to prevent the same from passing through the traps of basins, sinks, etc., and more particularly the provision of a chain or similar connection for the cap by means of which to secure it to the body of the tube, but still the necessity of screwing and unscrewing the cap is present. Other expedients require quite a departure from the ordinary type of tube manufactured and are either too expensive or impractical from a commercial standpoint.

With this in view, the object of my present invention is to provide a novel form of closure means having permanent connection with the tube body which will permit its free and ready displacement to open the tube and to close the same, and when closed will effectively retain the contents sanitary or in

the best condition to preserve the desired properties of the substances.

It may be further stated that another object in view is to provide a closure means of such a construction and arrangement as to tightly engage over the mouth or bore of the tube and will not be liable to bending or breakage in the natural handling of the container.

These and such other objects as may hereinafter appear are attained by the novel construction, combination and arrangement of parts to be hereinafter specifically described and claimed.

Reference will now be had to the accompanying drawings forming a part of this specification, wherein:

Figure 1 is an elevation of a collapsible tube having applied thereto my improved closure means.

Figure 2 is an enlarged detail view showing more clearly the closure means in its closed position.

Figure 3 is a detail view of the closure member alone.

Figure 4 is an enlarged view showing a modified construction of closure means within the purview of my invention.

Figure 5 is a sectional view taken about on the plane indicated by the line 5—5 of Figure 4.

Figure 6 is an enlarged view similar to Figures 2 and 4 and disclosing a further modification of the closure means.

Figure 7 is a detail view of the closure means shown in Figures 4 and 5.

Figure 8 is a detail view of the form of closure means employed in the construction disclosed in Figure 6.

Figure 9 is a fragmentary vertical sectional view through the mouth of the tube and showing the closed position of the cut-off member employed in the form of tube shown in Figure 2.

Throughout the following detailed description and on the several figures of the drawing, similar parts are referred to by like reference characters.

Referring to the drawing, 1 designates the body portion of the ordinary collapsible tube, and 2 the mouth or neck portion of the same. In providing for these improvements the mouth portion 2 of the tube is cut into from one side substantially half way through the neck or to a point intersecting the bore

of the tube at the mouth. At one side of the mouth the metal is constructed so as to form a pair of lugs 3 through which the pintle 4 passes to connect the closure member in a permanent manner to the mouth of the tube, as shown clearly in Figure 2.

By reference to Figure 3 it will be observed that the closure means 5 is of segmental form, having at one end the pintle 10 receiving eye 6 and at its opposite end the finger engaging projection 7 which projects slightly from the side of the tube to enable the user to swing the cut-off to and fro upon its pivot. Preferably I provide an extension 8 on the inner edge of this cut-off so that when in closed position the bore 9 of the tube, referring to Figure 9 of the drawing, is effectively covered, the cut-off being constructed to snugly fit within the groove 15 or cut-out portion of the mouth hereinbefore described and thus frictionally held in place. At the top the bore 9 of the tube is flattened as indicated at 9' so as to produce the ribboning of the contents as they are squeezed 20 from the tube in a well-known manner.

It will be apparent from the foregoing that a very simple arrangement is provided for both cutting off the flow of the contents from the tube and maintaining the tube 30 closed, the closure means being permanently connected to the body of the tube in a simple manner and therefore not liable to be lost or misplaced or dropped during use. By virtue of its mounting in the lateral cut-out 35 or groove of the mouth or neck of the tube, the likelihood of the cut-off becoming bent is reduced to a minimum.

In Figures 4 and 5 I have depicted a slight modification in the construction of 40 the cut-off. Here again this member is pivotally connected at one side of the mouth, but the top surface of the cut-off 5' is provided with a boss or upstanding projection 45 10, arcuate in form, and designed to function somewhat as a wedge primarily for the purpose of completely expelling the contents from the entrance or mouth of the bore when the cut-off is moved into closed position, so that no portion of the substance 50 will remain at the entrance to be exposed to contamination or to form a crust which would render subsequent discharge of the contents difficult. The top of the neck is 55 suitably cut out so as to receive this boss 10, as shown clearly in Figure 4.

The cut-off, it should be observed, at the pivotal end, is provided preferably with a shoulder or stop extension 11 which will limit the outward swinging movement of 60 the cut-off to the extent that it will only swing partially on the pivot or just sufficient to leave a narrow, flattened opening at the mouth through which the contents are discharged, an opening, in fact, equivalent to the slot opening 12 shown in the con-

struction of Figure 2. This shoulder projection may be applied to all forms of these cut-offs. Furthermore, it will be observed that the cut-off 5' of Figures 5 and 7 is constructed with a small extension 5^a which 70 will overlie and completely close the bore of the tube. This extension functions primarily as a cut-off, while the boss 10 acts to expel from the entrance the surplus material, as above stated.

A still further modification of that form of the cut-off of Figure 3 is disclosed in Figures 6 and 8 of the drawing, wherein the segmental member 5'' is formed with a bendable extension 13. This extension 13 80 is first bent upwardly and then over horizontally so that the horizontal portion will lie over the discharge opening 12 and effectively close this opening when the cut-off is in its closed position. Obviously this 85 prevents dust from gaining entrance into the short section of the bore immediately located at the outlet between the top surface of the tube neck and the cut-off seated in the lateral groove.

Other modifications may readily be made within the purview of this invention, and the scope of the claims hereto appended, without departing from the spirit of the invention.

Having thus described my invention, what I claim as new and desire to secure by Letters Patent is:

1. The combination with a collapsible tube of the class described having one end 100 formed with a discharge opening and laterally cut to provide a seat with a diametric wall, of a closure member pivotally connected at one side to swing within said seat and engage said wall, said member being 105 provided with a portion to cover the discharge opening of the tube.

2. The combination with a collapsible tube of the class described, the discharge portion of which is formed with a bore and 110 cut through from one side to a point beyond the bore of the tube and formed with an abutting wall, of a cut off member movable in said cut and having a face to engage said wall and a projected portion to intercept 115 and close the bore of the tube.

3. The combination with a collapsible tube of the class described, having its discharge portion formed with a bore and cut transversely from one side to a point intercepting the bore of the tube to provide a seat 120 having an end wall, of a segmental closure member hingedly connected to the tube at one side of the mouth to enter said seat and engage said wall, said closure member having an extension to overlie said bore and seat in a portion of the cut beyond the bore.

4. The combination with a collapsible tube of the class described having a mouth and discharge bore, of a closure member 130

pivottally mounted at one side of the mouth thereof and having means upstanding therefrom adapted to completely expel from the entrance to the bore of the tube any remaining material.

5. The combination with a collapsible tube of the class described, having a discharge bore and the mouth thereof cut through laterally to and intercepting the

bore to form a seat, a segmental cut-off slidably mounted in said seat, and having upstanding therefrom a projection constituting means for closing that portion of the bore of the tube lying above the cut-off when in closed position. 10

In testimony whereof I affix my signature.

ARTHUR H. SAUNDERS.
